[Term of Patent 3½ years]

P.

To all whom it may concern:

Be it known that I, ALFRED HEALD, of the city and county of Philadelphia, State of Pennsylvania, have produced or invented a Design for a Carpet-Pattern, of which the following is a specification:

The principal members of the pattern illustrated by the accompanying drawing are the square and cruciform figures A and B, the contiguous corners of which are connected together by a smaller figure, D, having four arms, *a a a a*, and a central ornament, *b*. The spaces between the several figures are occupied by foliated scrolls *d*. The internal ornamentation of the figures A and B is of a char-

acter so clearly shown in the drawing as to require no detailed description.

Irrespective of the colors employed, I claim—

The design for a carpet-pattern composed of figures A, B, and D, and the intervening ornamentation, all as described, and represented in and by the accompanying drawing.

In testimony whereof I have signed my name to this specification in the presence of two subscribing witnesses.

ALFRED HEALD.
